UNITED STATES PATENT OFFICE.

FRANK FABBRIN, OF TALLMAN, NEW YORK, ASSIGNEE, BY DIRECT AND MESNE ASSIGNMENTS, TO CONTINENTAL PRODUCTS CORPORATION, OF NEW YORK, N. Y., A CORPORATION OF DELAWARE.

UMBRELLA RIB AND SPREADER STRUCTURE AND METHOD OF PRODUCING THE SAME.

Application filed June 7, 1926. Serial No. 114,325.

This invention relates to umbrella structures and methods employed in their production, the same being in the nature of an improvement upon my co-pending application 5 Serial No. 87,133 filed Feb. 9, 1926.

The present invention comprehends an improved hingedly connected umbrella rib and spreader structure, and a method of producing the same, whereby a strong, durable, yet 10 inexpensive structure and method of production may be accomplished.

With the above recited and other objects in view, reference is had to the following specification and accompanying drawings in 15 which there is exhibited one example or embodiment of the invention which is in no way intended as a limitation upon the scope of the appended claims as it is to be clearly understood that variations and modifications 20 which properly fall within the scope of said claims may be resorted to when found expedient.

In the drawings—

Figure 1 illustrates the initial step in the 25 production of a set of hingedly connected ribs and structures;

Fig. 2 is a side view of the initial step in the method of producing the same;

Fig. 3 is a plan view illustrating the second step in the method;

Fig. 4 is a side view thereof;

Fig. 5 is a plan view of the third step in the method, and

Fig. 6 is a perspective view of a completed 35 hingedly connected rib and spreader element.

Referring to the drawings by characters of reference and particularly to Fig. 6, 10 designates the rib, 11 the spreader, and 12 and 13 the flexible connecting pieces between the 40 rib and spreader which serve to hingedly connect and reinforce the elements at this point.

In producing the hingedly connected rib and spreader elements, a strip of material A 45 of the desired length and width to produce a set of ribs, is used, upon which is superimposed a second strip B of the desired length and width to produce a similar number of spreaders. A strip of flexible material C of 50 a length approximately equal to the width of the strips A and B is laid transversely and adhesively secured to the upper surface of the strip A and the inner end of the strip B so that the strips are joined together at this

point. After the adhesive is set, the strip B 55 is swung relatively to the strip A so that it overlies the other portion of the strip A with the flexible strip C doubled upon itself, as illustrated in Fig. 4. A second flexible strip D of approximately the same size as the strip 60 C is laid transversely and adhesively secured to the upper surface of the strip A and the upper surface of the inner end of the strip B.

The next step consists in superimposing any desired number of the connected strips 65 upon each other in exact alinement and cutting the same completely through along the lines E, as illustrated in Fig. 5, so as to subdivide the same into a number of narrow pieces of uniform size to produce the finished 70 articles which are shown in Fig. 6.

Under this method it is obvious that hingedly connected and reinforced rib and spreader structures for umbrellas of the type specified may be produced in a minimum time and 75 at an extremely low cost.

What is claimed is:

1. The herein described method of producing a set of hingedly connected umbrella rib and spreader units, consisting in superimposing a pair of sheets of material upon each other with the end of one sheet disposed at substantially the medial portion of the other sheet, adhesively securing a transverse flexible strip to the inner end of the upper sheet 85 of material and to the lower sheet of material, swinging the upper sheet in an opposite direction to bend the flexible strip upon itself after the adhesive has set, applying a second strip of material adhesively to the inner end of the upper sheet and the upper face of the lower sheet, and simultaneously cutting the sheets and strips along parallel lines longitudinally of the sheets to provide a plurality of connected rib and spreader 95 units.

2. The herein described method of producing a plurality of sets of hingedly connected umbrella rib and spreader units, consisting in independently superimposing a number of 100 pairs of sheets of material upon each other with the end of one sheet of each pair disposed at substantially the medial portion of the other sheet, adhesively securing a transverse flexible strip to the inner end of the upper sheet of material and to the upper face of the lower sheet of material, swinging the upper sheet in an opposite direction to bend the 105

flexible strip upon itself after the adhesive has set, and applying a second strip of material adhesively to the inner end of the upper sheet and to the upper face of the lower sheet, 5 superimposing a plurality of said hingedly connected sheets upon each other in alignment, and simultaneously cutting the sheets and strips thereof along parallel lines longitudinally of the sheets to produce a plurality 10 of independent hingedly connected rib and spreader units.

3. The herein described method comprising hinging an end of one sheet of material to a medial portion of another sheet of material, and plurally dividing said hinged sheets. 10

4. The herein described method comprising hinging an end of an elongated sheet of material to a medial portion of a second elongated sheet of material, and dividing the hinged sheets by a plurality of parallel cuts.

FRANK FABBRIN.
